SAFETY MEANS FOR SWAGING MACHINES

Charles T. Brennan, Cheshire, Conn.

Application February 14, 1934, Serial No. 711,099

11 Claims. (Cl. 29—34)

In the operation of machines provided with tools for swaging, upsetting, trimming, extruding and punching metal in which blanks are cut from the end of a hot or a cold bar or rod and fed to the tools, it occasionally happens that a blank will become jammed or the tools will fail to properly function and if means are not provided for interrupting the effective action of the actuating elements when such failure occurs, parts of the mechanism or the tools become broken or seriously damaged.

This invention relates to means which is particularly adapted for machines of the class mentioned that will in a simple manner and without noise, excessive wear or undue strain render the actuating mechanism ineffective when conditions occur which will interfere with the normal operation of the machine.

The invention is adaptable to the connections between the driving mechanisms and the tools of various types of metal forming machines. For the purpose of disclosing a concrete embodiment the conception is, herein illustrated and described as designed for application to the cut-off mechanism of a machine in which a rod is entered and sections of its end cut off and carried into line with a cooperating punch and die that have complementary shapes for conforming the severed pieces. In this machine the end of the rod is severed and carried into line with the tools by a cutter on a bar that is reciprocated by a slide which is connected with a yoke on an eccentric disk that is driven by a crank operated from the driving shaft of the machine. In carrying out this invention the eccentric disk is operatively fastened to the yoke by a pin that has sufficient strength to withstand all normal strains but which will be sheared on the occurrence of excessive strain resulting from accidental conditions and allow the disk to turn in the yoke and become locked with the disk and yoke in such relation that their throw will be shortened from the normal throw.

In the accompanying drawing Fig. 1 shows a plan view of a swaging machine with a safety mechanism which embodies this invention applied between the main shaft and the cutting off tool slide.

Fig. 2 shows on larger scale a top view of the safety mechanism.

Fig. 3 shows a side view of the safety mechanism illustrated in Fig. 2.

Fig. 4 is a face view of the eccentric disk and yoke with portions broken away to expose the normal connections between the disk and yoke.

In the views only so much of the frame 1 of a machine of well known type as is necessary to an understanding of the application of the invention, is illustrated. Set in the front end of the frame of this machine is a die 2 coating with which for shaping the blanks is a punch 3 that is reciprocated at the proper times by the usual mechanism. The rod of stock 4 is advanced by the ordinary feeding means through an opening in the frame and its inner end 5 is cut off by the inward movement of a cutter blade 6, and the severed piece is, by the cutter blade assisted by the backing blade 7, carried into line with the punch and die by which the blank is to be conformed.

The backing blade is shown as fastened to a bar 8 that is moved in and out by the angle lever 9 which is connected by a link 10 with levers 11 that are actuated by cams 12 on the main shaft 13, after the manner set forth in Patent No. 1,897,359 issued to me Feb. 14, 1933. The cutter blade is illustrated as secured to a bar 14 that is moved in and out by the action of the cam groove 15 in the slide 16 as described in Patent No. 1,857,997 issued to me May 10, 1932.

On the outer end of the main shaft is a balance wheel 17 and fastened to this wheel is a crank disk 18 extending from which is a crank pin 19. This crank pin engages an eccentric disk 20 that is movably fitted in a yoke 21 which is connected by a link 22 with the cutter bar slide 16. The eccentric disk and yoke are normally held in fixed relation by a pin 23 that is tightly fitted in a hardened bushing 24 in the disk and a hardened bushing 25 in the yoke.

When the machine is operating normally the rotation of the crank, through the eccentric disk and connected yoke, the link and cam slide, reciprocates the cutter bar and causes the cutter to sever the end of the stock rod and carry the blank thus produced into line with the punch and die, and then return for cutting a following piece of the stock. However should there be an irregularity in the feed of the stock or a fault in the blank, or should the blank become jammed in or between the punch and die, or if for any other reason there should be interference with, or obstruction to, the proper action of the tools which offers excess resistance, the pin 23 will be sheared by the bushings 24 and 25 leaving the eccentric disk free to rotate in the yoke. When the eccentric and yoke are disconnected the effective throw of the crank is reduced to such an extent that the cutter bar is not reciprocated sufficiently for the cam to force the cutter in between

the tools, and thus the possibility of damage to the tools or injury to the operating mechanism is obviated.

To ensure the withdrawal of and for preventing the cutter blade from being carried between the tools, should the connection between the eccentric disk and yoke become sheared at the forward extremity of the stroke, where for a few degrees the disk and yoke in going past the center practically dwell and do not have action sufficient to withdraw the cutter bar, the edge of the disk may be provided with a slot 26, and a spring pressed pin 27 may be inserted through the yoke so as to project into this slot. The slot is long enough to allow the disk to go forward in the direction of shear the required amount to withdraw the cutting tool. At the end of the slot is a socket 28 into which the inner end of the pin will enter and again lock the disk and yoke together. With the disk and yoke locked in this relation their throw will be shortened and the throw of the crank will not be sufficient to again carry the cutter between the tools.

The invention claimed is:—

1. In combination with the driving mechanism and conforming tools of a machine of the character mentioned, a safety means comprising a crank rotated by the driving mechanism, an eccentric disk operatively engaged by said crank, a yoke fitted about said disk, means locking said disk to said yoke in one relation for normal action and locking the disk to the yoke in another relation upon interference with normal action of the tools, tool actuating means, and a connection between said yoke and said tool actuating means.

2. In combination with the driving mechanism and conforming tools of a machine of the character mentioned, a safety means comprising a crank rotated by the driving mechanism, an eccentric disk operatively engaged by said crank, a yoke fitted about said disk, a frangible pin extending through the yoke into the disk and normally locking said disk to said yoke, tool actuating means, and a connection between said yoke and said tool actuating means.

3. In combination with the driving mechanism and conforming tools of a machine of the character mentioned, a safety means comprising a crank rotated by the driving mechanism, an eccentric disk operatively engaged by said crank, a yoke fitted about said disk, frangible means insertable through the yoke into the disk and normally locking said disk to said yoke, a cam slide for causing the action of a tool, and a connection between said yoke and said slide.

4. In combination with the driving shaft and forming tools of a machine of the character mentioned, a safety means comprising a crank attached to the driving shaft, an eccentric disk operatively engaged by said crank, a yoke fitted about said disk, complementary bushings located in the disk and yoke, a frangible pin extending through said bushings and locking said disk to said yoke, tool actuating means, and a connection between said yoke and said tool actuating means.

5. A safety means connecting the driving mechanism with tools of a machine of the character mentioned, which comprises a crank, an

eccentric disk operatively engaged by said crank, a yoke fitted about said disk, and means locking said disk to said yoke and normally causing full throw of the eccentric and under abnormal conditions shortening the throw of the eccentric.

6. A safety means connecting the driving mechanism with tools of a machine of the character mentioned, which comprises a crank, an eccentric disk operatively engaged by said crank, said disk having a groove extending part way around its periphery, a yoke fitted about said disk, frangible means locking said disk to said yoke, and a pin extending through the yoke into said groove.

7. Safety means interposed between the driving mechanism and tools of a metal conforming machine, which comprises a crank, an eccentric disk operatively engaged by said crank, a yoke fitted about said disk, frangible means normally locking said disk to said yoke, said disk having a groove and locking socket, and a pin extending through the yoke into said groove and adapted to enter said socket for locking the disk and yoke in a different relation following the rupture of said frangible means.

8. Safety means interposed between the driving mechanism and tools of a metal conforming machine, which comprises a crank, an eccentric disk operatively engaged by said crank, a yoke fitted about said disk, frangible means normally locking said disk to said yoke, said disk having a locking socket in its periphery, and a pin extending through the yoke and adapted to enter said socket for locking the disk and yoke in a different relation following the rupture of said frangible means.

9. Safety means interposed between the driving mechanism and tools of a metal conforming machine, which comprises a crank, an eccentric disk operatively engaged by said crank, a yoke fitted about said disk with frangible means normally locking said disk to said yoke with the yoke in one relation to the crank, and means for locking the yoke and disk with the yoke in a different relation to the crank upon the rupture of said frangible means.

10. Means interposed between the driving crank and tool slide of a metal conforming machine, which comprises an eccentric disk operatively engaged by said crank, means connected to the tool slide and actuated by said disk, a frangible pin normally locking said means to the disk in one relation to the crank, and a pin adapted to lock said means to the disk in a different relation to the crank upon the rupture of said frangible pin.

11. Means for converting rotatory motion into reciprocatory motion which comprises a rotatable crank, a disk eccentrically connected with and adapted to be rotated by the crank, and means connected by a frangible member with the disk and adapted to be reciprocated by the combined effect of the crank and disk under normal conditions and said frangible member intact and to be reciprocated by the effect of the crank only under abnormal conditions and said frangible member fractured.

CHARLES T. BRENNAN.
